(57) **CLAIM**

The ornamental design for the photographic lip retractor, as shown and described.

DESCRIPTION

FIG. 1 is a perspective view of an embodiment of the photographic lip retractor showing our new design;
FIG. 2 is a top plan view thereof;
FIG. 3 is a side elevation view with the opposite side a mirror image thereof;
FIG. 4 is a bottom plan view thereof;
FIG. 5 is an end elevational view thereof; and,
FIG. 6 is a front elevational view of the photographic lip retractor according to the present invention.
